UNITED STATES PATENT OFFICE.

HARRY RALPH RICARDO, OF LONDON, ENGLAND.

INTERNAL-COMBUSTION ENGINE.

1,297,401.

Specification of Letters Patent. Patented Mar. 18, 1919.

Application filed August 13, 1917. Serial No. 186,082.

To all whom it may concern:

Be it known that I, HARRY RALPH RICARDO, subject of the King of England, residing at London, in England, have invented 5 certain new and useful Improvements in Internal-Combustion Engines, of which the following is a specification.

This invention relates to internal combustion engines of the type employing super-compression and in which air or gas or both comprised in the combustible charge is cooled after preliminary compression and before entering the working cylinder. The present invention has for its object to effect 10 certain improvements in the construction 15 arrangement and operation of the cooling device.

According to this invention there is mounted on one side of the engine cylinder 20 a chamber which is provided with a non-return inlet valve and this chamber communicates with the interior of the cylinder through a passage leading from one end of the cylinder and through a second passage 25 in which may be a cock or throttle leading to ports in the cylinder wall. In the cylinder reciprocates a differential piston one face of which acts as a pump in that end of the cylinder which is in communication with the 30 chamber. Means are provided for cooling the gas, which is drawn through the inlet valve in the chamber into the end of the cylinder, after this gas has been compressed in the cylinder and as it passes through the 35 chamber and by way of the ports into the working end of the cylinder. The cooling may be effected by a water jacket or a series of water pipes which pass through the chamber in either case constituting part of the 40 cooling water system of the engine. Alternatively the induction pipe through which explosive mixture is conveyed to the combustion chamber of the cylinder or what may be termed its working end, may be led 45 through the cooling chamber so that the heat from the gases which are compressed in the pump end of the cylinder as they pass through this chamber will be transferred to or taken up by the cool gases flowing through 50 the induction pipe. Either air or explosive mixture may be compressed in the pump end of the cylinder and after compression and cooling this gas is introduced into the working end of the cylinder as a super- 55 charge.

In the accompanying drawings, Figure 1 is a vertical sectional elevation of the cylinder of an internal combustion engine to which the present improvement is applied.

Fig. 2 is a similar view showing an alternative structure and arrangement for the cooling chamber.

Fig. 3 is a cross section of the cooling chamber shown in Fig. 2, the section being 65 taken on the line 3-3 in that figure.

Fig. 4 is a similar view showing a modification of the invention.

Like letters indicate like parts throughout 70 the drawings.

The internal combustion engine illustrated operates on the four stroke cycle the charge being subjected to compression in two stages. The cylinder A is so formed that one end A' 75 constitutes the usual combustion chamber, in the head of which are formed the usual inlet and exhaust ports that are controlled, respectively, by valves S S', while the other end opens into a chamber A² in which air or an explosive mixture is compressed by one face of the piston B. The latter in the preferred construction is formed with a trunk B' of less diameter than the piston portion B this trunk reciprocating in a cylinder C which is correspondingly of less 80 diameter than the cylinder A and mounted at the open end of the cylinder A. The piston is thus provided with an annular pump face B² by means of which air or gas can be drawn into and compressed in the chamber A². This air or gas after compression passes into an annular chamber A³ and thence through ports A⁴ into the cylinder A when these ports are uncovered by the piston B at 85 the end of the outstroke of the latter.

According to this invention the air or gas after compression in the chamber A² is cooled in transit to the chamber A³ and before it passes through the ports A⁴ into the cylinder A. This cooling may be effected by the device illustrated in Fig. 1 where as will be seen there is mounted on the side of the cylinder a chamber D of suitable dimensions in one side of which is arranged a non-return valve controlling inlet ports D' through 100 which the air or gas is drawn by the suction of the annular face B² of the piston B. This chamber D is partially divided by a partition D² so as to form a passage D³ which leads to the pump chamber A² and a passage 105 110

D⁴ which leads to the annular delivery chamber A⁴. In the latter passage is conveniently arranged a throttle or cock E by means of which the quantity of air or gas flowing 5 through the ports A⁴ into the cylinder A can be regulated. Running across the chamber D are a series of tubes F through which water can be circulated. As illustrated these tubes pass at each end through opposite walls 10 of the chamber D and terminate in chambers F', F². The latter is in communication with the jacket space G surrounding the cylinder A. The lower chamber F' is conveniently in communication with a pump or other 15 source of supply by means of which cooling water is delivered to the engine.

On the instroke of the piston B a charge of air or gas is drawn through the ports D' into the chamber D over the pipes F and 20 into the pump chamber A² and the other end of the cylinder A. On the outstroke of the piston B this air is compressed in the chambers A² and D and is then subjected to the 25 cooling effect of the water passing through the pipes F. Toward the end of the outstroke of the piston B the ports A⁴ are uncovered and the cooled charge then enters the cylinder A where it either has a scavenging 30 effect if its entry takes place after explosion of the main charge and while the exhaust valve is open or when the entry of the cooled charge occurs at the end of the suction stroke this cooled charge mingles with the main combustible charge which 35 fills the cylinder A.

Referring to Figs. 2 and 3 the passage D⁴ through which the gases pass from the pump chamber A² to the ports A⁴ leading into the cylinder is here formed as a flattened tube 40 the shape of which is clearly indicated in the cross section in Fig. 3. This flattened tube D⁴ leads out of the chamber D³ in which are the valve-controlled inlet ports D' and is carried through a water jacket F³. In the 45 opposite end of the flattened tube D⁴ is disposed the throttle E. The water jacket F³ is preferably in communication with the water circulation system of the engine, a pipe F⁴ leading from this water jacket to the water jacket space G surrounding the cylinder A. In the construction illustrated 50 in Fig. 3 the water jacket F³ is formed as a flattened tube inclosing the flattened gas passage tube D⁴ but this water jacket may be otherwise shaped as for instance when 55 several cylinders are disposed next to each other. In that case the tubes D⁴ of the several cylinders may be disposed adjacent and if desired connected or formed as a single casting the whole row of tubes being arranged within a single casing constituting the water jacket F³.

In the modification illustrated in Fig. 4 the cooling of the charge of air or gas which 60 is compressed in the chambers A² and D is

effected by carrying through the chamber D the induction pipe H through which the main combustible charge passes on its way to the cylinder A. The cooling is also assisted in this case by providing extensions 70 D⁵ of the chamber D which have radiating gills D⁶ formed on their exterior. An appreciable length of the induction pipe H is thus brought within the chamber D of which the outer walls are air-cooled by the gills D⁶ on the extensions D⁵. The charge of air or gas after and during compression has to pass through the passage D³ into the chamber D and thence past the throttle E through the passage D⁴ into the annular chamber A³ and so through the ports A⁴ into the cylinder A. With this construction the heat from the compressed charge within the chamber D is used to advantage in raising the temperature of the gases passing through the induction pipe H.

What I claim as my invention and desire to secure by Letters Patent is:—

1. In an internal combustion engine, the combination of a cylinder provided with inlet and exhaust ports at one end and formed as a pump chamber at its other end, a piston in the cylinder adapted to compress gases in the pump chamber to form super-charges, the cylinder being provided with auxiliary ports adapted to be uncovered by the piston toward the end of its out stroke, a valve controlling the supply of gas to the pump chamber, a passage connecting the pump chamber with said auxiliary ports, whereby gases compressed in the pump chamber will be admitted to the combustion chamber of the cylinder as a super-charge when the auxiliary ports are uncovered on the outstroke of the piston, and means for cooling the gases in their passage from the pump chamber to the piston controlled ports of the cylinder.

2. An internal combustion engine including in combination, a cylinder with inlet and exhaust ports at one end and having a pump chamber at its other end, a piston slideable in the cylinder, means actuated by the piston to compress gases in said chamber, means to convey the compressed gases to the cylinder, means to admit said gases as a supercharge to the cylinder near the end of the out-stroke of the piston, and means to absorb heat from said gases before they enter the cylinder.

3. In an internal combustion engine the combination of a cylinder provided with inlet and exhaust ports at one end formed with a pump chamber at its other end, a piston in the cylinder, auxiliary ports in the wall of the cylinder positioned where they will be uncovered by the piston toward the end of its outstroke, a passage leading from the pump chamber to the piston controlled ports in the cylinder, a valve-controlled inlet port toward the pump chamber end of this pas-

sage, a throttle in this passage positioned toward the end adjacent to the piston controlled ports, and means for cooling the super-charge gases after compression in the 5 pump chamber as they traverse the passage leading to the piston controlled ports as set forth.

4. In an internal combustion engine the combination of a cylinder formed with a 10 pump chamber at one end thereof, and having inlet and exhaust ports at its opposite end, a piston in the cylinder, ports in the wall of the cylinder positioned where they will be uncovered by the piston toward the 15 end of its outstroke, a chamber in communication with the pump chamber end of the cylinder, a valve-controlled inlet port in this chamber, a passage leading from this chamber to the piston controlled ports in the cylinder, a throttle in this passage positioned 20 toward the end adjacent to the piston controlled ports, and means for cooling the super-charge gases after compression in the pump chamber as they traverse the passage leading to the piston controlled ports as set forth.

5. In an internal combustion engine the combination of a cylinder formed with a 25 pump chamber at one end thereof, and having inlet and exhaust ports at its opposite end, a piston in the cylinder, ports in the wall of the cylinder positioned where they will be uncovered by the piston toward the end of its outstroke, a passage leading from the 30 pump chamber to the piston controlled ports in the cylinder, a valve-controlled inlet port in this passage, and a passage through which water can so pass as to cool the super-charge gases after compression in the pump chamber as they traverse the passage leading to the piston controlled ports to serve as a super-charge as set forth.

6. In an internal combustion engine the combination of a cylinder provided with a 35 main inlet and exhaust ports and formed with a pump chamber at one end thereof, a piston in the cylinder, auxiliary ports in the wall of the cylinder positioned where they will be uncovered by the piston toward the end of its outstroke, a chamber in communication with the pump chamber end of the cylinder, a valve-controlled inlet port in this chamber, a passage leading from this chamber to the piston controlled ports in the 40 cylinder, and a passage through which water can so pass as to cool the super-charge gases after compression in the pump chamber as they traverse the passage leading to the piston controlled ports as set forth.

60 7. In an internal combustion engine the combination of a cylinder provided with main inlet and exhaust ports and formed with a pump chamber at one end thereof, a piston in the cylinder, auxiliary ports in the 45 wall of the cylinder positioned where

they will be uncovered by the piston toward the end of its outstroke, a chamber in communication with the pump chamber end of the cylinder, a valve-controlled inlet port in this chamber, a passage leading from this chamber to the piston controlled ports in the cylinder, a throttle in this passage positioned toward the end adjacent to the piston controlled ports, and a passage through which water can so pass as to cool the super-charge gases after compression in the pump chamber as they traverse the passage leading to the piston controlled ports as set forth. 70

8. In an internal combustion engine the combination of a cylinder provided at one 80 end with main inlet and exhaust ports and formed with a pump chamber at its other end, a piston in the cylinder, auxiliary ports in the wall of the cylinder positioned where they will be uncovered by the piston toward the 85 end of its outstroke, a passage leading from the pump chamber to the piston controlled ports in the cylinder, a valve-controlled inlet port in this passage, and a water jacket surrounding such portion of this passage as to effect cooling of the gases after compression in the pump chamber as they traverse the passage leading to the piston controlled ports to serve as a super-charge as set forth. 90

9. In an internal combustion engine the combination of a cylinder formed with a pump chamber at one end thereof, and having main inlet and exhaust ports at its other end, a water jacket for the cylinder, a differential piston operative to compress gaseous charges in the pump chamber end of the cylinder, to serve as super-charges, auxiliary ports in the wall of the cylinder positioned where they will be uncovered by the 100 piston toward the end of its outstroke, a chamber in communication with the pump chamber end of the cylinder, a valve-controlled inlet port in this chamber, a passage leading from this chamber to the piston controlled ports in the cylinder, a throttle in this passage positioned toward the end adjacent to the piston controlled ports, a water jacket surrounding such portion of this passage as to effect cooling of the gases after 105 compression in the pump chamber as they traverse the passage leading to the piston controlled ports, and a communication between this water jacket and the cylinder water jacket as set forth. 110

10. In an internal combustion engine the combination of a cylinder formed with a pump chamber at one end thereof, and having main inlet and exhaust ports at its other end, a piston in the cylinder, ports in the 115 wall of the cylinder positioned where they will be uncovered by the piston toward the end of its outstroke a passage leading from the pump chamber to the piston controlled ports in the cylinder, a portion of the length 120

4
of this passage being constituted by a flattened tube, a valve-controlled inlet port in said passage, a throttle positioned in this passage toward that end of the flattened portion which is adjacent to the piston controlled ports, and a passage through which water can so pass as to cool the gases after compression in the pump chamber as they traverse the flattened portion of the passage 10 leading to the piston controlled ports as set forth.

11. In an internal combustion engine the combination of a cylinder formed with a pump chamber at one end thereof, and having main inlet and exhaust ports at its other end, a piston in the cylinder, auxiliary ports in the wall of the cylinder positioned where they will be uncovered by the piston toward the end of its outstroke, a chamber in communication with the pump chamber end of the cylinder, a valve-controlled inlet port in this chamber, a passage leading from this chamber to the piston controlled ports in the cylinder, this passage being formed for the greater part of its length as a flattened tube, a throttle in this passage positioned toward the end adjacent to the piston controlled ports, and a passage through which water can so pass as to cool the gases after compression in the pump chamber as they traverse the flattened tubular passage to the piston controlled ports as set forth.

12. In an internal combustion engine the

combination of a cylinder formed with a pump chamber at one end thereof, and having main inlet and exhaust ports at its other end, a water jacket for the cylinder, a differential piston operative to compress gaseous charges in the pump chamber end of the cylinder, to serve as super-charges, auxiliary ports in the wall of the cylinder positioned where they will be uncovered by the piston toward the end of its outstroke, a chamber in communication with the pump chamber end of the cylinder, a valve-controlled inlet port in this chamber, a passage leading from this chamber to the piston controlled ports in the cylinder, this passage being formed for the greater part of its length as a flattened tube, a throttle in this passage positioned toward the end adjacent to the piston controlled ports, a water jacket surrounding such portion of this passage as to effect cooling of the gases after compression in the pump chamber as they traverse the passage to the piston controlled ports, and a communication between this water jacket and the cylinder water jacket as set forth.
